UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

LOOM.

1,295,371.

Specification of Letters Patent. Patented Feb. 25, 1919.

Application filed September 17, 1917. Serial No. 191,672.

To all whom it may concern:

Be it known that I, ALONZO E. RHOADES, a citizen of the United States, residing at Hopedale, county of Worcester, and State 5 of Massachusetts, have invented an Improvement in Looms, of which the following description, in connection with the accompanying drawing, is a specification, like characters on the drawing representing like 10 parts.

This invention has for its object the provision of means to prevent the filling in the shuttle from being thrown by momentum out of the shuttle recess at the time the shuttle 15 is boxed.

In the case particularly of heavy grades 20 of filling such as employed in weaving duck or other heavy materials, the sudden stoppage of the shuttle when boxed at the end 25 of the pick causes the filling to be thrown off the end of the filling carrier by momentum and thrown up more or less out of the shuttle recess. In the case of automatic weft replenishing looms and other looms 30 employing a self-threading shuttle, the result is not infrequently to cause the shuttle to unthread by the filling being thrown out through the threading slot and in the case of these and other types of looms, the result 35 not infrequently is for the filling to be caught between the shuttle and the binder and other parts of the loom and be pinched or broken or entangled.

This invention provides means, such for 40 example as a pad of bristles which extends over and covers the filling on the filling carrier in the shuttle recess at the time the shuttle is boxed and thus prevents the filling from being thrown by momentum out of the 45 shuttle recess upon the sudden stoppage of the shuttle. These means are preferably supported from the frame of the loom so as to be out of the way of the mechanism for effecting transfer if the loom be of the replenishing type.

These and other objects of the invention 50 will appear more fully from the accompanying description and drawing and will be particularly pointed out in the appended claims.

The drawings represent so much of a loom of the automatic weft replenishing type known as the "Northrop" loom as is necessary to disclose the invention together with

a preferred form of the invention embodied 55 therein.

In the drawings,

Figure 1 is an elevation partially in vertical cross-section of a portion of the loom looking toward the transfer end; 60

Fig. 2 is a top plan view of a portion of the loom shown in Fig. 1.

The present invention is not concerned with the particular type or construction of loom and that type of loom illustrated is 65 presented simply to effect the disclosure of the invention.

The loom shown is of the well-known "Northrop" type. The loom side 1 constituting a portion of the loom frame carries the 70 hopper 2 containing the supply of fresh filling carriers 3. When replenishment takes place, the usual transerrer 4 is operative to force a filling carrier out of the hopper into the shuttle then on the lay therebeneath and 75 thereby to force out from the shuttle the exhausted filling carrier.

The lay 5 carried by the lay swords, one of which 6 is illustrated, carries on each end the usual shuttle box 7, the one at the transfer end of the lay being herein illustrated. 80

The shuttle 8 is recessed at 9 from top to bottom in the usual manner to receive the filling carrier herein shown as a bobbin 10. When the shuttle is of the self-threading type such as is used in the automatic weft replenishing loom, it is provided with some form of slot extending from the recess 9 into the eye from which the filling extends and in threading the shuttle the filling is simply drawn off from the filling carrier and passed down through these slots until it enters and reeves out through the eye. In the case of the automatic loom, this 85 threading of the shuttle is performed automatically. 90

In the course of the operation of weaving, at the end of each pick, the shuttle is suddenly stopped by contact with the picker 12 and suitable mechanism such as a binder 13 or loom check. When the filling is of a heavy weight, such as employed for example in the weaving of duck and other coarse materials, the weight of the filling is such as to give it considerable momentum. Consequently upon the sudden stoppage of the shuttle, at the time it is boxed at the end of the pick, the filling, especially that por- 100
105

tion next to be drawn off from the filling carrier, and that portion extending from the filling carrier to the shuttle eye, is lifted or thrown by its momentum and not infrequently is thrown up out of the shuttle recess. This results, in the case of the self-threading shuttle, in the filling being thrown out of the threading slot thus unthreading the shuttle or it results in the filling being caught between the shuttle and the walls of the shuttle box or the binder or other parts of the loom and becoming pinched, caught or broken.

This invention provides means for preventing the filling from thus being thrown by momentum out of the shuttle recess upon the stoppage of the shuttle. Such means may be provided at both sides of the loom if found desirable but are particularly of use at the transfer end of the loom herein illustrated, where the tendency is to throw the filling off the end of the filling carrier.

Preferably, this means is carried by, or supported from, the loom frame so that it does not move with the lay and consequently does not interfere with the operation of the transfer or replenishing mechanism. But this is only essential in the case of a weft replenishing loom.

30 A preferred construction for this purpose is herein illustrated as embodying the invention and comprises a bracket 13 bolted or otherwise secured at 14 to a portion of the loom frame and bent so as to project above 35 the shuttle box on the lay at the time the shuttle is being boxed. This arm has secured thereto, as by the screws 15, a plate 16 which in the form illustrated is provided on its lower face with a pad of bristles 17. 40 This plate is of sufficient area to cover the filling in the shuttle recess which is likely to be loosed and thrown out of the shuttle recess by momentum upon the stoppage of the shuttle and is herein shown as covering 45 all the filling on the filling carrier in the shuttle.

The provision of a pad of bristles has been found an effective expedient for holding the filling in place and enabling the device to be

brought in close proximity to the top of the 50 shuttle box and to yield as the lay beats up.

It will be seen that by mounting this device from the loom frame, it is held in position out of the field of action of the transerrer but in a position where it secures the desired result.

Having fully described my invention, what I claim as new and desire to secure by Letters Patent is:

1. A loom comprising a lay, a shuttle box 60 on the lay, and means extending over and substantially covering the body of filling on the filling carrier in the shuttle at the time the shuttle is boxed whereby the filling is prevented thereby upon the stoppage of the 65 shuttle from being thrown by momentum out of the shuttle recess.

2. A weft replenishing loom comprising a lay, a shuttle box on the lay, and means carried by the loom frame and extending over and substantially covering the body of filling on the filling carrier in the shuttle at the time the shuttle is boxed whereby the filling is prevented thereby upon the stoppage of the shuttle from being thrown by 75 momentum out of the shuttle recess but without interfering with the action of weft replenishment.

3. A loom comprising a lay, a shuttle box on the lay, a self-threading shuttle, means 80 carried by the frame and extending over and substantially covering the body of filling on the filling carrier in the shuttle at the time the shuttle is boxed whereby the filling is prevented thereby upon the stoppage of 85 the shuttle from being unthreaded from the shuttle by momentum.

4. A loom comprising a lay, a shuttle box on the lay, a pad of bristles supported from the frame, and extending over and covering 90 the filling on the filling carrier in the shuttle at the time the shuttle is boxed whereby the filling is prevented thereby upon the stoppage of the shuttle from being thrown by momentum out of the shuttle recess. 95

In testimony whereof, I have signed my name to this specification.

ALONZO E. RHOADES.
